E. J. PHILLIPS

PUTTY KNIFE AND POINT HOLDER

Filed Oct. 22, 1923.

Lead D. J. Evans

WITNESS:

Edward S. Phillips
INVENTOR
BY *Victor J. Evans*

ATTORNEY

UNITED STATES PATENT OFFICE.

EDWARD J. PHILLIPS, OF HARTFORD, CONNECTICUT.

PUTTY KNIFE AND POINT HOLDER.

Application filed October 22, 1923. Serial No. 670,155.

To all whom it may concern:

Be it known that I, EDWARD J. PHILLIPS, a citizen of the United States, residing at Hartford, in the county of Hartford and 5 State of Connecticut, have invented new and useful Improvements in Putty Knives and Point Holders, of which the following is a specification.

This invention relates to tools, particularly 10 to putty knives used by painters, glaziers and others in the securing of glass panes in windows and the like, and has for its object the provision of a novel putty knife which has its blade and handle formed from a single 15 piece of sheet metal cut and bent to shape, the advantage being that the device is less expensive to manufacture than the ordinary type while at the same time it will be more rapid and durable.

20 An important object is the provision of a putty knife of this character in which the handle is so formed as to provide a compartment for the storage of the points commonly used by glaziers for holding the pane in 25 place preparatory to putting the handle having a removable closure cap.

With the above and other objects and advantages in view the invention consists in the details of construction to be hereinafter 30 more fully described and claimed and illustrated in the accompanying drawings, in which:

Figure 1 is an elevation of one form of the device,

35 Figure 2 is a view of the blank from which it is formed this view illustrating the lines of bending,

Figure 3 is a longitudinal section,

40 Figure 4 is a cross section on the line 4—4 of Figure 1,

Figure 5 is a view similar to Figure 1 showing a slight modification and

Figure 6 is a view of the blank from which it is formed.

45 Figure 7 is a detail section on the line 7—7 of Figure 1.

Referring more particularly to the drawings, and especially Figures 1 to 4, the numeral 10 designates the blank from which the 50 knife is formed, which blank includes a relatively wide portion 11 designed to form the handle and a portion 12 which constitutes the blade. This blade portion has its corners preferably rounded off as indicated at 13 and where it joins the handle portion 11 it is

constricted or reduced in width as indicated at 14. At the lower corners of the handle portion 11 are extensions 15 for a purpose to be described. In this form of the device it is intended that the handle be somewhat 60 tapered and for this reason the side edges 16 of the handle portion 11 of the blank are inclined as shown.

To form the device, the handle portion 11 has its sides rolled up with the edges 16 65 brought together as shown in Figures 1 to 4. The blank is bent at the neck 14 so that the blade will be offset with respect to the handle. The extensions 15 are bent at right angles to the blank and co-operate with the 70 blade to form a bottom closure which makes the hollow handle constitute a receptacle conveniently usable for the storage of glaziers', points and the like.

I also provide a cap 17 having a depending 75 skirt or flange 18 adapted to telescope within the open end of the handle and this skirt is split or slotted as indicated at 19 so that it will have sufficient resilience to grip frictionally within the handle and prevent removal.

In Figures 5 and 6 I have shown a slight modification in which the construction is exactly the same except that the blade 20 is smaller than the blade 12 and the handle 85 portion 21 of the blank has its side edges 22 parallel instead of inclined so that the completed handle 23 will be cylindrical or substantially so. The same cap is used in this instance in exactly the same manner as 90 in the first described form.

From the foregoing description and a study of the drawings it will be apparent that I have thus provided a simple and consequently very inexpensive putty knife which 95 has the great advantage of being formed from a single piece of material cut and bent to shape. As there are no separate parts it is apparent that there is no likelihood of derangement and if material of suitable gage 100 is used the tool should have sufficient strength to be capable of long use. Of course the device possesses the further advantage of constituting a container for holding glaziers' points so that it may be most convenient in 105 use and well adapted for its purpose.

While I have shown and described the preferred embodiment of my invention it is of course to be understood that I reserve the right to make such changes in the form, 110

construction and arrangement of parts as will not depart from the spirit of the invention or the scope of the subjoined claims.

Having thus described my invention I claim:

1. A putty knife formed from a single piece of sheet metal formed from a blank including a blade portion and a handle forming portion integral therewith, the sides of the handle portion being designed to be folded over to define a hollow handle, the outer corners of the handle forming portion nearest the blade being formed with curved extensions designed to lie against the blade when the handle is formed to define a bottom for the hollow handle whereby the latter may be used as a receptacle for containing glaziers' points.

2. A putty knife formed from a single piece of sheet metal formed from a blank including a blade portion and a handle forming portion integral therewith, the sides of the handle portion being designed to be folded over to define a hollow handle, the outer corners of the handle forming portion nearest the blade being formed with curved extensions designed to lie against the blade when the handle is formed to define a bottom for the hollow handle whereby the latter may be used as a receptacle for containing glaziers' points, and a cap frictionally and telescopically engaged within the handle.

In testimony whereof I affix my signature.

EDWARD J. PHILLIPS.
